UNITED STATES PATENT OFFICE.

JOHN D. WALSH, OF LOCKPORT, NEW YORK, ASSIGNOR TO AMERICAN DISTRICT STEAM COMPANY, OF LOCKPORT, NEW YORK, A CORPORATION OF NEW YORK.

METER.

No. 796,883.

Specification of Letters Patent.

Patented Aug. 8, 1905.

Application filed December 30, 1903. Serial No. 187,201.

To all whom it may concern:

Be it known that I, JOHN D. WALSH, a citizen of the United States, residing at Lockport, in the county of Niagara and State of New York, have invented certain new and useful Improvements in Meters; and I do hereby declare the following to be a full, clear, and exact description of the invention, such as will enable others skilled in the art to which it appertains to make and use the same.

One important object of my invention is to provide an efficient, accurate, and wear-resisting device for measuring and metering liquids which shall be noiseless in its operation, simple in its construction, and free from jar in operation and which may be readily adjusted to meter the same and varying quantities of liquid matter at the same time and varying quantities at different times.

Another important object is so to construct the dash-pot and the bucket and its rock-shaft, suitably positioned upon a supporting member, that these parts (namely, the bucket, dash-pot, and rock-shaft) may be readily removed from the device and be used with any appropriate or preferred form of casing, or, in fact, without a casing, enabling me to manufacture these parts and sell them separately from my casing, the buyer being enabled to position these parts in an appropriate casing to suit himself or to use them without a casing, as desired.

Another important object is to provide a novel and improved form of dash-pot.

Another important object is to provide a dash-pot with means for maintaining the same constantly supplied with liquid for a purpose hereinafter appearing; and my invention consists of the constructions, combinations, and arrangements of parts herein described, illustrated, and claimed.

In the accompanying drawings, Figure 1 is a vertical longitudinal section of the casing, taken along line $z-z$ of Fig. 4 and showing in rear elevation the interior parts of the device, one position thereof being shown in dotted lines. Fig. 2 is a transverse vertical section taken along line $y-y$ of Fig. 4. Fig. 3 is a side elevation of my device, a part of the end casing being removed and showing other parts of the casing in section; and Fig. 4 is a plan view of the device, the casing and parts of the device being removed along line $z-z$ of Fig. 1

and showing the outline of the interior parts in dotted lines.

Referring to the drawings, A indicates the casing, to which is suitably secured the front cover or plate a and preferably constituting a supporting member for certain parts herein-after described, this cover-plate being removable. Removably secured to the top of the casing A is the cap a^2 , resting upon the interior flange a^1 . On the under side of the cap are formed downward projections a^3 , adapted to engage the inner walls of the casing and rest upon the interior flange and hold the cap in place. Similar projections or lugs a^4 , near the center of the cap, are arranged to center the top of a screen E, hereinafter described.

The upper portion of the casing A is formed with threaded inlet-openings a^5 , and the lower portion is formed with similar openings adapted to form outlets therefor, both inlet and outlet pipes being adapted to be connected with supply and discharge pipes, respectively. Extending across the interior of the upper portion of the casing and below the inlet-openings a^5 is the horizontal plate or flange a^7 , which may be formed integral with the walls of the casing. This plate is provided with an opening a^8 to receive a nozzle D.

Secured to the front cover a of the casing A, on the inner side thereof, is a bracket B, extending nearly across the interior of the casing A. Rotating in bearings b b^2 , respectively, in the bracket B and the cover-plate a is a rock-shaft b^3 . Secured to the upper surface of the lower part of the bracket B are upward-extending stops b^4 , and below the plane of these stops and the outlet-openings a^6 are my peculiar form of dash-pots b^5 , desirably provided with perforations b^6 through their lower peripheries, both the stops and dash-pots being formed integrally with the bracket or suitably secured thereto. My dash pot or pots are preferably formed with flaring sides b^7 and with a cone-shaped under periphery b^8 . The central portion of the dash-pot is desirably solid, as at b^9 , the sides of this solid portion preferably flaring with a curvature conforming to or paralleling the flare of the sides b^7 , the solid portion b^9 , with the sides b^7 , forming chambers b^{10} , preferably independent of each other—that is, non-communicating—and of a size larger than the toes of plungers, hereinafter described.

The curvature of the sides of the dash-pot chambers is very important with a bucket having a rigid plunger or plungers. If the plungers were pivoted, the sides of the dash-pot chambers could be made straight, as usual; but with a preferably rigid plunger, as in my construction, and for a dash-pot chamber of my desired size it is my novel idea to make the sides of the dash-pot chambers a^{10} curve, (in parallelism, desirably,) so that the plunger-toes may swing clear into the chambers a^{10} without wedging tight therein, as would be the case were the sides of the dash-pot chambers straight.

Extending longitudinally of the interior of the casing A is open-ended bucket C, formed with a plurality of compartments c , separated by a partition c' . Secured to the under side of the bucket C is saddle-bracket c^2 , which is suitably secured to the rock-shaft b^3 , as by set-screws c^4 . Projecting downward from the under side of the saddle-bracket are bosses c^4 , into which are tapped screws c^5 , arranged to come into contact alternately with the stops or bumpers b^4 , carried by the bracket, when the bucket is rocked.

Secured to the under side of the bucket are plungers, each preferably comprising an upper toe or foot c^7 , a vertically-elongated body portion c^{8a} , and a lower toe or foot c^8 of less area than the chambers b^{10} in the dash-pots b^5 and being arranged to strike alternately therein as the bucket is rocked, thus providing an effective cushioning means preventing noise.

Extending through the opening a^8 of the horizontal plate or flange a^7 is a nozzle D, which may be threaded into engagement with the walls of the opening. Formed on the upper portion of the nozzle are shoulders d^3 , adapted to rest upon the plate a^7 , and projecting upward above the shoulders d^2 are lugs d^3 , formed to engage the lower end of a screen E. The lower end of this nozzle may be tapered and extended to within a short distance of the top of the bucket.

The screen E is of any suitable material and arranged with its top end e centered around the projections a^4 of the cap a and is there held between these projections and the interior flange a' . The lower end of the screen is centered around the projections d^3 of the nozzle D and rests upon the shoulders d^2 thereof and is held in position by these parts.

A registering device F is located on the outside of the casing A, as on the cover a , and comprises any suitable mechanism for registering the oscillation of the rock-shaft b^3 .

It will be noted that my dash-pot is not fastened to the floor of the casing, and therefore that the same, together with the bracket B, the bucket, and rock-shaft supported by the cover-plate a , may be removed readily from the casing. Consequently these parts may be manufactured and sold separately and connected up to any suitable form of casing.

In the operation of my invention liquid is admitted through the inlet-openings a^5 , passes through the screen E, and thence down through the nozzle D into one of the compartments c of the bucket C, as indicated by the arrows in the drawings. The screen E serves to prevent sediment in the water or liquid from passing through, and such sediment finds its way downward to the flange a^7 , where it will be below the plane of the top of nozzle D and out of the current of the liquid passing through the device. When sufficient liquid has passed into the compartment c , as shown in Fig. 1 by dotted line G, the bucket will be rocked downward by the weight of the water, the shaft will be turned, and the water will run out of the end of the compartment, thence into the bottom of the casing A, filling the dash-pots b^5 through the perforations b^6 , and when the water reaches the level of the outlet-openings a^6 will be carried off. By having the dash-pots on a lower plane than the outlet-openings liquid is retained in them, and this is a novel feature of my invention. The lower toes c^8 of the plungers being of less area than the dash-pots, the liquid can escape only around the edges of the plungers when they enter the dash-pots at each downward movement of the bucket, forming a liquid cushion. The velocity of the bucket is decreased by this arrangement, the noise avoided which would occur if in the operation of the device the adjusting-screws c^5 were allowed to strike the bumpers b^4 without decreasing the momentum of the bucket. As the empty compartment rises pressure of the water on the upper side of the toes c^8 operates as a slight brake on the ascending plunger, and the oscillating action of the bucket is thereby rendered somewhat less abrupt, thus tending to avoid jar and strain.

The device may have liquid supplied by gravity, or the same may be pumped into the casing through the openings a^5 .

The quantity of water allowed to flow into one of the compartments c is regulated by the adjusting-screw c^5 . It is obvious that should either of the adjusting-screws be carried farther into the boss c^4 its corresponding bucket or compartment would travel a relatively increased distance downward, and the liquid in the opposite compartment would thereby be allowed to rise to a higher elevation, and a greater quantity of the liquid would be contained in that compartment. The capacity of the other compartment would remain unchanged unless the other adjusting-screw was changed to project a greater or less distance out of the boss. It will thus be seen that the device will operate to meter different quantities at the same time and may be adjusted to meter varying quantities at different times.

It is important in a device of the character of my invention that exact quantities of water shall be measured at each oscillation of the

bucket, and to this end positive means insuring such precise measurement must be provided. In experiments leading up to the perfection of my present construction, forming the subject-matter of this application for patent, I first used a spring plate or sheet in the path of movement of the oscillating bucket, against which the bucket would strike, this spring-plate serving as a stop or abutment limiting the degree of downward movement of the bucket, the same as is shown by patents in the art; but I found not only would the bucket striking against the spring-plate cause a very great and objectionable degree of noise, but the spring-plate would yield to a certain extent, and thus by reason of such yielding the correct and desired quantity of water could not be measured. In other words, the spring-plate was a yielding stop. My abutments or bumpers b^4 , in connection with the adjusting-screws c^6 , form a rigid stop, so that exact quantities of water may be positively measured.

Having thus fully described my invention, what I claim as new, and desire to secure by Letters Patent, is—

1. In a liquid-measuring device, an oscillating bucket provided with plungers on its under side, and a dash-pot arranged beneath and in the line of travel of the bucket, said dash-pot presenting water-holding chambers having sides of a curvature corresponding approximately to the angle formed by the plungers upon entering the chambers, whereby danger of jamming or wedging of the plungers in the chambers is obviated.

2. In a liquid-measuring device, a bucket supported for oscillatory movement and provided with plungers on its under surface, dash-pots arranged beneath the bucket and in the path of movement of the plungers, and provided with perforations on their under periphery, and means to keep the dash-pots constantly supplied with water or liquid.

3. In a liquid-measuring device, an oscillating bucket provided with plungers on its under side, and a dash-pot arranged beneath and in the line of travel of the bucket, said dash-pot presenting independent, non-communicating, water-holding chambers having sides of a curvature corresponding approximately to the angle formed by the plungers upon entering the chambers, whereby danger of jamming or wedging of the plungers in the chambers is obviated.

4. In a liquid-measuring device, an oscillating bucket provided with plungers on its under side, having toes or feet, and a dash-pot arranged beneath and in the line of travel of the bucket, said dash-pot presenting water-holding chambers having sides of a curvature corresponding approximately to the angle formed by the plungers upon entering the chambers, whereby danger of jamming or

wedging of the plungers in the chambers is obviated.

5. In a liquid-measuring device, a bucket supported for oscillatory movement, and provided with plungers on its under surface, a dash-pot arranged beneath the bucket and in the path of movement of the plungers, and presenting water-holding chambers, each chamber independent of the other, that is, non-communicating, and having sides of a curvature corresponding approximately to the angle formed by the plungers upon entering the chambers, whereby danger of jamming or wedging of the plungers in the chambers is obviated.

6. In a liquid-measuring device, a bucket supported for oscillatory movement, and provided with plungers on its under surface, dash-pots arranged beneath the bucket and in the path of movement of the plungers, and an inclosing casing providing means to keep the dash-pots constantly supplied with liquid; the said plungers terminating at their free ends in feet, presenting a broad contact-surface adapted to impinge with the water in the dash-pots.

7. In a liquid-measuring device, a bucket supported for oscillatory movement, and provided with plungers on its under surface terminating at their free ends in feet, dash-pots arranged beneath the bucket and in the path of movement of the plungers, and provided with chambers of a size larger than the feet of the plungers, and an inclosing casing providing means to keep the dash-pots constantly supplied with liquid; said feet of the plungers presenting a broad contact-surface adapted to impinge with the water in the dash-pots.

8. In a liquid-measuring device, a bucket supported for oscillatory movement, and provided with plungers on its under surface, the plungers being provided with toes or feet, and dash-pots arranged beneath the bucket and in the path of movement of the plungers, said dash-pots being formed with flaring sides and with a central solid portion with flaring sides of a curvature to correspond with the first-mentioned flaring sides, whereby chambers are formed in the dash-pots of a size larger than the toes or feet of the plungers.

9. In a liquid-measuring device, a bucket supported for oscillatory movement, and provided with plungers on its under surface, the plungers being provided with toes or feet, and dash-pots arranged beneath the bucket and in the path of movement of the plungers, said dash-pots being formed with a cone-shaped under surface or periphery, with flaring sides, and with a central solid portion with flaring sides, of a curvature to correspond with the first-mentioned flaring sides, whereby chambers are formed in the dash-pots of a size larger than the toes or feet of the plungers.

10. In a liquid-measuring device, a bucket supported for oscillatory movement, and pro-

vided with plungers on its under surface, the plungers being provided with toes or feet, and dash-pots arranged beneath the bucket and in the path of movement of the plungers, said dash-pots being formed with a perforated, cone-shaped, under surface, with flaring sides, and with a central solid portion with flaring sides of a curvature to correspond with the first-mentioned flaring sides, whereby chambers are formed in the dash-pots of a size larger than the toes or feet of the plungers, and means to keep the chambers of the dash-pots constantly supplied with liquid.

11. In a liquid-measuring device, a bucket supported for oscillatory movement, and provided with plungers on its under surface, means constructed and arranged to adjust the arc of tilting movement described by the bucket, a dash - pot arranged beneath the bucket and in the path of movement of the plungers and presenting water-holding chambers, each chamber independent of the other, that is, non-communicating, and having sides of a curvature corresponding approximately to the angle formed by the plungers upon entering the chambers, whereby danger of jamming or wedging of the plungers in the chambers is obviated; and means to keep the dash-pots constantly supplied with liquid.

12. In a liquid-measuring device, a casing having inlet and outlet openings, an oscillating bucket supported in the casing, and provided with plungers on its under surface, and dash-pots arranged beneath the bucket and in the path of movement of the plungers, and in a plane beneath the outlet-openings of the casing, and means to keep the dash-pots constantly supplied with liquid.

13. In a liquid-measuring device, provided with rigid plungers on its under surface, an oscillating bucket and a dash-pot arranged beneath and in the line of travel of the bucket, said dash-pot presenting water-holding chambers having sides of a curvature corresponding approximately to the angle formed by the plungers upon entering the chambers, whereby danger of jamming or wedging of the plungers in the chambers is obviated.

14. A gravity-operated, liquid-measuring apparatus having a casing constructed with inlet and outlet openings, an oscillating bucket supported in the casing, vertically-elongated plungers, with toes, carried by the bucket, and dash-pots arranged beneath and in the line of travel of the plungers.

15. A gravity-operated, liquid-measuring apparatus having a casing constructed with inlet and outlet openings, an oscillating bucket supported in the casing, means to limit movement thereof, vertically-elongated plungers, with toes or feet, carried by the bucket, and dash-pots arranged beneath and in the line of travel of the plungers.

16. A gravity-operated, liquid-measuring apparatus having a casing constructed with in-

let and outlet openings, an oscillating bucket supported in the casing, means to limit the movement thereof, and means within the casing constructed to render the operation of the bucket noiseless, comprising plungers secured to the bucket and having their free ends expanded into flat planes and dash-pots arranged to receive the flat planes.

17. A liquid-measuring apparatus having a casing, inlet and outlet openings in the casing, a bracket secured in the casing, a rock-shaft supported on the bracket and the casing, a double bucket secured to the rock-shaft, means to limit movement of the bucket, and means constructed to render its operation noiseless, comprising plungers secured to the under side of the bucket and having their free ends expanded into flat planes, and dash-pots on the bracket arranged to receive the plungers.

18. In a gravity-operated, liquid-measuring apparatus, the combination of a casing constructed with inlet and outlet openings, an oscillating bucket supported in the casing, means to limit the oscillation thereof, and means within the casing, constructed to render the operation of the bucket noiseless, comprising plungers having their upper ends secured to the bucket and their lower ends expanded into flat planes, and dash-pots below the bucket arranged to receive the lower ends of the plungers on each oscillation of the bucket.

19. A liquid-measuring device comprising a casing having inlet and outlet openings, an oscillating bucket supported in the casing, a saddle - bracket secured under the bucket, means carried by the bracket to positively adjust the capacity of the bucket, rigid bumpers located below the bracket arranged to coact with the means for adjusting the capacity of the bucket, and means to render the operation of the bucket noiseless.

20. A liquid-measuring device, comprising a casing having inlet and outlet openings, a bracket secured to the inner wall of the casing, bushings carried by the inner end of the bracket and the casing, a rock-shaft secured in the bushings, a bucket having two compartments secured on the rock-shaft, and means carried by the bracket to positively adjust the capacity of either compartment of the bucket, and means to render its operation noiseless.

21. A gravity-operated, liquid-measuring device, comprising a casing having inlet and outlet openings, a bracket secured to the inner wall of the casing, a rock-shaft carried by the bracket and the casing, a double bucket secured on the rock-shaft, bumpers carried by the bracket and bosses carried by the bucket to limit the movement thereof, and dash-pots on the bracket to render the operation of the bucket noiseless.

22. A liquid-measuring device comprising a casing, inlet and outlet openings therein, a bracket secured to the inside of the casing, a rock-shaft carried by the bracket and the cas-

ing and having one end projecting through the casing and adapted to engage registering mechanism to register the movement of the shaft, a bucket carried by a saddle-bracket secured to the shaft, means carried by the saddle-bracket to positively adjust the capacity of the bucket, and means carried by the bracket to render the operation of the bucket free from noise and jar.

23. In a meter, the combination of a casing having inlet and outlet openings, a screen in the upper portion thereof, means for centering and securing the screen in operative position, a double bucket constructed with open ends and bosses secured to the under side thereof, a bracket secured to the inner side of the casing, a rock-shaft carried by the bucket and one wall of the casing and secured to the bucket, dash-pots in the lower portion of the bracket, plungers carried by the bracket and arranged to enter the dash-pots on the downward movement of the bucket and decrease the momentum thereof, bumpers carried by the bracket arranged to come into contact with the bosses carried by the bucket on its downward movement, and adjusting-screws carried by the bosses arranged to adjust the capacity of the bucket.

24. In a meter, comprising a casing having inlet and outlet openings in the upper and lower portions thereof, respectively, the combination of a bracket secured to the inside of the casing, a rock-shaft carried by the bracket and the casing, an oscillating, open-ended, two-compartment bucket secured to the rock-shaft by set-screws and formed with bosses on the under side thereof and having adjusting-screws therein, bumpers carried by the

bracket arranged to come into contact with the bosses on the bucket on its downward movement and limit the movement thereof, plungers carried by the bucket, and dash-pots carried by the bracket arranged to receive the ends of the plungers on the downward movement of the bucket.

25. An open-ended compartment meter-bucket, comprising a body portion, a saddle-bracket secured to the under side of the bucket, bosses on the under side of the bucket constructed with adjustable screws therein, and plungers secured to the bucket and having their free ends expanded into planes.

26. A meter having a casing restricted in its upper portion, an interior flange near the top thereof, a cap having projections thereon arranged to engage the walls of the casing, an interior flange arranged intermediate of the top and bottom of the restricted portion of said casing and formed with an opening therein, a screen arranged between the two interior flanges, a nozzle through the lower flange having upward projections arranged and adapted to hold the screen in engagement with the projections of the cap, inlet-openings in the upper and outlet-openings in the lower part of the casing, an oscillating bucket supported in the interior of the casing, and means to permit registering of its oscillation, means to render its action noiseless, and means to adjust its capacity.

In testimony whereof I affix my signature in the presence of two subscribing witnesses.

JOHN D. WALSH.
